Ebenezer Beard
Screw Patent

The Schedule referred to in these Spellers Patent and making part of
the same containing a description in the words of the said Ebenezer Beard
himself of his improvement in the screw Water Wheel

To all persons to whom these presents shall come Ebenezer Beard of Charles-
ton in the County of Middlesex Commonwealth of Massachusetts you
the man. sends greeting. Be it known that the said Ebenezer Beard has
discovered, invented, constructed & made & applied to use a new & useful
improvement in propelling vessels of all descriptions called the screw
water wheel to be applied to vessels of all descriptions either by hand
power or steam & to be placed either at the sides stern of any vessel or at the
sides only or at the stern only. The said Screw Water Wheel may contain
either two or four paddles placed at quarter slant to each other which said
screw wheel is built whether embracing two or four paddles is to be placed
under the surface of the water. In testimony that the above is a true Spec-
ification of my said improvement or discovery as above described
I have hereunto set my hand & seal the fifteenth day of December in the year
of our Lord 1827
